UNITED STATES PATENT OFFICE.

IRA KRUGER, OF ABERDEEN, SOUTH DAKOTA.

WAGON-TONGUE.

1,283,415.

Specification of Letters Patent. Patented Oct. 29, 1918.

Application filed May 4, 1918. Serial No. 232,675.

To all whom it may concern:

Be it known that I, IRA KRUGER, a citizen of the United States, residing at Aberdeen, in the county of Brown, in the State 5 of South Dakota, have invented a new and useful Wagon-Tongue, of which the following is a specification.

My invention relates to improvements in a wagon tongue with a view to securing its 10 ready adjustment to wagons or trucks of varying widths between the "hounds" and in order to adapt it to use when the wagon or truck to which it is attached is used either with horses or as a "trailer". I attain these 15 objects by the mechanism illustrated in the accompanying drawings wherein like parts are designated by like letters and wherein Figure 1 is a top view of the tongue as extended for use with horses, and Fig. 2 is a 20 top view of the tongue as folded for use on a "trailer"; and Figs. 3 and 4 are views of details as hereinafter described.

In Fig. 1 *w* shows the front wheels of a wagon on the front axle *a*. *h h* show the 25 "hounds" common to most heavy wagons and trucks. *b* shows the two iron sides or members of the rear section of the tongue, which may be of any suitable width and depth of band or channel or other suitable section of 30 iron. *c* and *c'* are eyelets suitably attached to the side members *b* of the tongue by rivets or otherwise. *f f* are loops or eyelets turned on the ends of the eyelets *c* and serving as points of attachment for the draft bars *g g*, 35 one of which passes under the doubletree *j* (as shown in a side view in Fig. 4) and one passes above the doubletree. A draw-bolt *i* passes through loops on the ends of the draft bars *g g* and through the doubletree, 40 all as clearly shown on the drawings. *e* is the bolt or traction rod upon which the tongue turns vertically and by which it is held to and between the hounds.

t t are turnbuckles set between the side 45 members *b* of the tongue for the purpose of adjusting them firmly to the inner surfaces of the hounds *h h*. Through the ends of the turnbuckle screws, and within the eyelets *c* and *c'*, are drilled holes *d* (Fig. 3) through 50 which are placed cotter-pins to hold the screws and prevent their turning in the eyelets. *B B* are the side-members of the forward section of the tongue, (the folding section) which is pivotally connected to the 55 sides *b* of the rear section by bolts or rivets

at *k k*, and about these, as on an axis, the forward section of the tongue turns into the folded position shown in Fig. 2. A drawbar *m* passes through the rear end of the forward section and through the guide-plate 60 *l* and terminates in the eyelet *o*. About the drawbar *m* is the spring *s*, held in position by the nut *n*. When the tongue is extended, as shown in Fig. 1, a bolt *p* is passed through the side members *b* and through the eyelet *o* 65 on the end of the drawbar *m* thus holding the forward section of the tongue in rigid alinement with the inner or rear section.

The side members *B B* of the forward section of the tongue may be drawn together 70 at their outer ends as shown and suitably fastened to a wooden member or filler *u*, the end of which may be finished with an eyelet *v* such as is seen on most wagon tongues. But the details of the finishing of the end of 75 the tongue do not constitute an element in this invention.

If it is desired to use the wagon or truck as a trailer it is desirable to be able to quickly shorten the tongue and to have a spring pull 80 on the drawbar. In that case, and with this improved tongue, remove the bolt *p* and turn the forward section of the tongue on its axial bearings *k k* into the position shown in Fig. 2. Then replace the bolt *p* which now 85 holds the two sections of the tongue in rigid juxtaposition as shown in Fig. 2. The spring draw-head is now in position to use by attachment to the draw-eyelet *o*.

Having thus described my invention what 90 I claim as new, novel, and useful, and on which I desire Letters Patent is:—

1. In a wagon tongue the combination of a rear section composed of two side members of iron adjustably spaced between the hounds 95 of the wagon by means of turnbuckles; and a forward section composed of two connected side members of iron pivotally connected to and between the side members of the rear section whereby said forward section may be turned backward into a horizontal position in alinement with and between the side members of the rear section.

2. In a wagon tongue the combination of a rear section composed of two side members of iron adjustably spaced between the hounds of the wagon by means of turnbuckles; and a forward section composed of two connected side members of iron pivotally connected to and between the side mem- 110

bers of the rear section whereby said forward section may be turned backward into a horizontal position in alinement with and between the side members of the rear section; and a spring-controlled drawbar set between the sides of the rear end of the forward section, and forming the forward end

of the tongue when the forward section thereof is folded backward into a horizontal position in alinement with and between the side members of the rear section of the tongue.

IRA KRUGER.
